DESCRIPTION

FIG. 1 is a left side elevational view of an elastomeric syringe actuator, showing my new design;

FIG. 2 is a top plan view thereof;

FIG. 3 is a right side elevational view thereof;

FIG. 4 is a front elevational view thereof;

FIG. 5 is a rear elevational view thereof;

FIG. 6 is a longitudinal cross-sectional view thereof, taken along line 6—6 of FIG. 1;

FIG. 7 is a lateral cross-sectional view thereof, facing rearwardly, taken along line 7—7 of FIG. 6;

FIG. 8 is a lateral cross-sectional view thereof, facing forwardly, taken along line 8—8 of FIG. 6; and,

FIG. 9 is an exploded bottom plan view thereof.
